UNITED STATES PATENT OFFICE.

LEONE TAGLIAFERRI, OF GENOA, ITALY.

ELECTRIC FURNACE.

Application filed March 25, 1920. Serial No. 368,584.

To all whom it may concern:

Be it known that I, LEONE TAGLIAFERRI, a subject of the King of Italy, and resident of Genoa, Italy, have invented certain new and useful Improvements in Electric Furnaces, of which the following is a specification.

The present invention relates to improvements in electric furnaces and more particularly to the means for supplying and distributing the electric current to the electric furnaces for melting steel, brass, bronze copper, and aluminum alloys.

The purpose of the invention is to attain a better distribution of the heat upon the surface of the bath, cutting out of operation the bottom of the furnace, and if necessary, also the bath itself.

A further purpose is to obtain a better regulation and control of the temperature, and as a consequence, of the melting operation, by means of a certain number of arcs, and moreover to eliminate excessive variations of the load during the starting.

According to the invention, because of the special arrangement of the supplying electric circuits, the furnace may be grounded, thus attaining a greater safety for the operators.

For a better understanding of the present invention, the same is described with reference to the accompanying drawings, in which are represented the several steps and circuits diagrams for furnaces supplied with two phase or three phase electric circuits.

In the drawings:

Fig. 1 shows the first step in the working of a furnace supplied with three phase current, in which the body of the furnace constitutes the neutral and in which the arc is formed between the electrodes, that is, between the phases and the neutral.

Fig. 2 shows the second step, that is, the melting having been obtained, the additional electrodes are taken apart, the arc being directly formed between the phase and the bath which is the neutral.

Fig. 3 shows the same type of furnace in which the electrodes are connected independently in pairs (one horizontal and the other vertical) with each phase of the circuit.

Fig. 4 is a view showing how, by means of a suitable connection, the three electrodes may be star connected to form a single arc above the bath.

Figs. 5, 6, 7 and 8 are views showing the invention applied to a two phase circuit.

Referring to the figures in particular, Fig. 1 shows an electric furnace —A— provided with three electrodes —B—, each connected to one phase of a three phase circuit. —C— indicates the furnace bottom, —D— the mass of material to be melted. On the side walls of the furnace are located three additional electrodes —E—, which are positioned in such manner to have their axes meet the axes of the electrodes —B—. A good disposition of the electrode is illustrated by the figures, in which the electrodes —B— are located at the vertex of a triangle, the electrodes —E— forming an angle of 120°. The latter are connected to the neutral wire of the circuit. The initial step of the operation is performed by advancing the electrodes —E— so that an arc may be produced between each of them and one of the electrodes —B—, the arcs being thus formed above the mass to be melted.

The melting operation will begin because of the heat developed by the arcs, that is for reverberation, until, by means of any suitable device, the two sets of electrodes are moved apart, leaving the arc to be formed directly between the electrodes —B— and the mass —D— as it is shown in Fig. 2.

Fig. 3 shows the invention as applied to the electrodes connected in pair, each pair being connected to a phase of the three phase circuit. In this case it is evident that it is possible to obtain a heat control between very wide limits, because it is possible to cut out, and to regulate, by increasing or decreasing the power, any of the three pair of electrodes and consequently any of the three arcs, leaving in operation one or two electrodes.

Fig. 4 is a view showing an arrangement similar to that of Fig. 1, the only difference residing in the fact that in this instance the vertical electrodes are adapted to be displaced so that they may be cut out of the circuit, the arc being maintained between the melting mass and the side electrodes —E—.

Figs. 5, 6, 7 and 8 show a certain number of arrangements similar to those described above, the supplying circuit being a two phase circuit.

I claim as my invention:—

1. In an electric furnace for melting metal, two sets of electrodes, the separate

- electrodes of one set being each connected to the source of current to be in one phase thereof and the electrodes of the other set being connected to the neutral of the source 5 of current and to the body of the furnace, and said electrodes being positioned so that the axes of one set cross the axes of the other set and each set being movable relative to the other set and the body of the 10 furnace, so that arcs may be produced either between the two sets of electrodes above the bath or the one set of electrodes and the metal carried by the body of the furnace.
- 15 2. In an electric furnace for melting steel or metallic alloys, two sets of electrodes supplied with multiphase current, the number of the electrodes of each set corresponding to the phases of the supplying circuit, 20 said electrodes being placed so that the axes of the electrodes of one set cross the axes of the electrodes of the other set, and one set of electrodes being movable respectively to the other set.
- 25 3. In an electric furnace for melting steel or metallic alloys; two sets of electrodes, one of which is fixed relative to the other; a starting circuit passing through the electrodes of both sets, the arc being initially 30 formed above the mass to be melted; said starting circuit being varied to make it pass through the fixed set of electrodes and the melting mass, when the movable set of electrodes is cut out of the circuit, the arc being then formed directly between the 35 relatively fixed set of electrodes and the melting mass.
4. In an electric furnace for melting steel or metallic alloys; means for supplying and distributing multiphase electric current; comprising two sets of electrodes, the electrodes of one set of which are respectively connected to each phase of the circuit, the electrodes of the other set being connected to the neutral through the body of the furnace, the arc being initially formed above and then directly with the melting mass.
5. In an electric furnace for melting steel or metallic alloys; means for supplying and distributing alternating electric current, 50 comprising two sets of electrodes, one set of which is movable relative to the other and out of the circuit, the electrodes of the set remaining in the circuit being star connected, the arc being formed and maintained above the molten bath.

In testimony whereof I have hereunto signed my name in the presence of two witnesses.

LEONE TAGLIAFERRI.
